US0D1008620S

(12) **United States Design Patent** (10) **Patent No.:** **US D1,008,620 S**
(45) **Date of Patent:** **** Dec. 26, 2023**

(54) **SHOE**

(71) Applicant: **NIKE, Inc.**, Beaverton, OR (US)

(72) Inventors: **Tom Ceurvels**, Portland, OR (US);
Zach F. Fitean, Portland, OR (US);
Ethan Lee, Portland, OR (US);
Tianhan Zhang, Portland, OR (US)

(73) Assignee: **NIKE, Inc.**, Beaverton, OR (US)

(***) Term: **15 Years**

(21) Appl. No.: **29/856,438**

(22) Filed: **Oct. 13, 2022**

(51) LOC (14) Cl. **02-04**

(52) U.S. Cl.

USPC **D2/960; D2/959**

(74) Attorney, Agent, or Firm — Banner & Witcoff, Ltd.

(57) **CLAIM**

The ornamental design for a shoe, as shown and described.

DESCRIPTION

FIG. 1 is a rear perspective view of a shoe showing our new design;

FIG. 2 is a side view thereof; and,

FIG. 3 is a front perspective view thereof.

The broken lines depicting the remainder of the shoe form no part of the claimed design.

1 Claim, 3 Drawing Sheets
